UNITED STATES PATENT OFFICE.

WILLIAM H. PHILLIPS, OF TERRE HAUTE, ASSIGNOR OF ONE-THIRD TO JOHN HERMAN KIRKHOFF AND GEORGE F. KIRKHOFF, BOTH OF INDIANAPOLIS, INDIANA.

OIL-GAS BURNER.

SPECIFICATION forming part of Letters Patent No. 460,657, dated October 6, 1891.

Application filed February 28, 1891. Serial No. 383,250. (No model.)

To all whom it may concern:

Be it known that I, WILLIAM H. PHILLIPS, a citizen of the United States, residing at Terre Haute, in the county of Vigo and State 5 of Indiana, have invented certain new and useful Improvements in Oil-Gas Burners; and I do hereby declare the following to be a full, clear, and exact description of the invention, such as will enable others skilled in 10 the art to which it appertains to make and use the same.

This invention relates to oil-gas burners; and it consists in the novel construction and combination of the parts hereinafter fully described and claimed.

In the drawings, Figure 1 is a longitudinal section through the burner, and Fig. 2 is a cross-section taken on the line $x-x$ in Fig. 1.

A is the pipe through which the oil-gas is 20 caused to flow from any approved form of reservoir.

B is an outer pipe concentric with the pipe A. Air is caused to flow through the pipe B and mix with the gas inside the tip C, which 25 is secured to the end of the pipe B. The mixed air and gas passes through the aperture c in the tip and is there ignited. The other end of the pipe B is screwed into one end of a T junction-piece b.

D is a nipple screwed into the other end of the said junction-piece b. The end of the gas-pipe A is screwed into the nipple D, so 30 that all these above-described parts are rigidly connected together. A pipe a is also 35 screwed into the nipple, and is adapted to connect the burner with the reservoir.

E are three spring-wires having their ends twisted together at e, so that they are firmly

united. These wires are provided with inwardly-projecting hooks g on their free ends. 40 The wires are inclined inward at e' from the hooks for a short distance, and are then inclined outward at f until they reach the point f'. The wires are thrust within the gas-pipe and they bear against the inside of the pipe 45 at the point f' and are held in position by their own elasticity. The hooks catch all foreign substances which may pass up the pipe with the gas and are easily removed from the pipe and cleaned when necessary. 50

What I claim is—

1. In an oil-gas burner, the combination, with the internal gas-pipe, of the air-pipe concentric with the gas-pipe, the tip secured to the air-pipe, and the spring-wires supported 55 inside the gas-pipe, said wires being twisted together at one end and provided with inwardly-projecting hooks and inclined portions at the other end, substantially as and for the purpose set forth. 6c

2. In an oil-gas burner, the combination, with the internal gas-pipe, of a nipple screwed onto the end of the gas-pipe, a T junction-piece screwed onto the said nipple concentric with the gas-pipe, the air-pipe screwed into 65 the other end of the said junction-piece, the tip secured to the end of the air-pipe over the end of the gas-pipe, and the hooked wires supported inside the gas-pipe, substantially as and for the purpose set forth. 70

In testimony whereof I affix my signature in presence of two witnesses.

WILLIAM H. PHILLIPS.
